O. C. SIMMONS

WINDOW SHADE SUPPORT

Filed April 2, 1925

Inventor
Oscar C. Simmons

By *Oscar C. Simmons*
Attorney

UNITED STATES PATENT OFFICE.

OSCAR C. SIMMONS, OF DALLAS, TEXAS.

WINDOW-SHADE SUPPORT.

Application filed April 2, 1925. Serial No. 20,219.

To all whom it may concern:

Be it known that I, OSCAR C. SIMMONS, a citizen of the United States, residing at Dallas, in the county of Dallas and State of Texas, have invented a new and useful Window-Shade Support, of which the following is a specification.

This invention aims to provide novel means whereby a window shade or the like may be shifted bodily, in a vertical direction, so that it may be used in connection with the upper sash of a window or with the lower sash of the window at the will of an operator.

Figure 1 shows in elevation, a window casing whereunto the device forming the subject matter of this application has been attached; Figure 2 is a section on the line 2—2 of Figure 1; Figure 3 is a section on the line 3—3 of Figure 1; Figure 4 is an end elevation of the movable carrier frame.

The numeral 1 marks a window casing made up of stiles 2, a lintel 3 and a sill 4. In carrying out the invention, there is provided a movable carrier frame 5 including side members 6 connected near to their lower ends by a cross rod 7 and connected near to their upper ends by a cross rod 8. At their upper ends, the side members 6 of the frame 5 are cut away to form shoulders 9 and to form reduced extensions 10 at the upper ends of the members 6. Brackets 11 are provided and are made in any desired way, depending upon what kind of a protection is to be used. Assuming that an ordinary spring-actuated shade 12 is employed, the brackets are constructed accordingly. Each bracket comprises a base 14, an outer flange 15 and an inner flange 16,

the flanges 15 being adapted, as shown at 17, to carry the roller of the shade 12. The reduced extensions 10 of the side members 6 of the frame 5 are secured to the inner flanges 16 of the brackets 11, the bases 14 of the brackets resting on the shoulders 9.

In this way, an unusually strong construction is afforded, and because the side members 6 of the frame 5 are cut away to form the shoulders 9, the brackets 11 will fit up closely against the window casing 1, when the carrier frame 5 is in the raised position depicted in Figure 1.

Radius arms 18 are supplied. The lower

ends of the radius arms 18 are pivoted at 19 to the inner surfaces of the stiles 2 at 55 points about midway between the upper and lower ends of the casing 1. The radius arms are pivoted at 20 to the side members 6 of the frame 5, at points between the ends of the side members 6. Offset keepers 21, 60 which may be resilient, are secured to the lintel 3. Forwardly extended spring latches 22 are attached to the stiles 2 of the casing 1, the latches having inclined ends 23. Stops 24 are mounted on the inner surfaces of 65 the stiles 2 near to the sill 4.

When the shade 12 is to be used on the upper part of the window, the device is arranged as shown in Figure 1. Then the base portions 14 of the brackets 11 rest 70 against the casing 1 and are engaged behind the resilient keepers 21, the side members 6 of the carrier frame 5 being engaged by the latches 22, as shown in Figures 1 and 3, to hold the carrier frame 5 in its elevated position.

Using the rod 7 as a handle, the operator may bring the carrier frame 5 downwardly, the frame swinging on the pivot elements 20, and the radius arms 18 swinging downwardly on their pivotal mountings 19, the side members 6 of the frame 5 abutting against the stop 24, and the shade 12 then being so positioned that it will cooperate with the lower part of the window. In a like manner, the carrier frame 5 may be swung upwardly by means of the rod 7, the base portions 14 of the brackets 11 engaging behind the keepers 21, and the side members 6 of the frame 5 being directed 85 into engagement with the latches 22 by the inclined ends 23 of the latches.

Although the frame 5 has been shown as carrying a spring-actuated shade roller and a shade 12, it will be understood that the device may be used with an ordinary window curtain or anything else which it is desired to hang before a window.

I claim:

In a device of the class described, a carrier frame having its upper and lower edges free, the frame being provided with mechanism for supporting a window hanging, radius arms pivoted to the frame intermediate the ends of the frame, and means for 105 pivotally mounting the radius arms on a

window casing at a point about midway between the upper and lower ends of the casing, the radius arms extending upwardly from said means when the frame is elevated enough to dispose said mechanism at the top of a window casing, the radius arms being of such length, and said means being so

located, that when the frame is swung downwardly, practically all of the upper half of the casing will be uncovered.

In testimony that I claim the foregoing as my own, I have hereto affixed my signature.

OSCAR C. SIMMONS.
